UNITED STATES PATENT OFFICE

CHARLES J. FANCHER, OF WINDSOR, VERMONT, AND ROBERT A. JOHNSON, OF LONG-MEADOW, MASSACHUSETTS, ASSIGNEES, BY MESNE ASSIGNMENTS, TO WOODWARD, HUBBARD COMPANY, OF HILL, NEW HAMPSHIRE, A CORPORATION OF NEW HAMPSHIRE

BLANK FEEDING MECHANISM

Original application filed January 12, 1927, Serial No. 160,639. Divided and this application filed December 21, 1927. Serial No. 241,575.

Our invention relates to improvements in mechanism for assembling into units or sticks of a predetermined number of objects, such as glaziers' points, the same being a divisional part of our application for Letters Patent of the United States, filed January 12, 1927, Serial No. 160,639.

The primary object of our invention is to produce highly efficient mechanism for dividing into units or sticks of predetermined lengths or numbers, from trains of objects, such as glaziers-points, whereby the sticks objects or points produced are in condition suitable for being packed into boxes, and for use when removed from said boxes.

It may be noted, in passing, that with this mechanism a mechanical count of the points or other objects, after they have been cut and as they pass on their way to be boxed or otherwise disposed of, is made.

A further object is to provide mechanism of this character with means which is comparatively simple to convey or transfer the sticks, after being cut from the trains, from a fixed carrier to a fixed slide, in order to enable said sticks to move on toward the boxing mechanism by gravity, and properly to control such movement.

Another object is to afford convenient means for applying powder to the sticks for the purpose of facilitating the movement thereof and preventing them from becoming stuck together after being packed in their boxes.

Other objects and advantages will appear in the course of the following description.

A preferred embodiment of the invention, whereby we attain the objects and secure the advantages of the same, is illustrated in the accompanying drawings, and we will proceed to describe the invention with reference to said drawings, although it is to be understood that the form, construction, arrangement, etc., of the parts in various aspects are not material and may be modified without departing from the spirit of the invention.

In the drawings, in which like reference characters designate like parts throughout the several views, Figure 1 is a back side elevation of the front-end portion of a glaziers-

point machine with which the assembling mechanism is associated or in which it is incorporated; Fig. 2, a front or right-hand end elevation of said machine; Fig. 3, a rear end elevation of the carrier of said machine, and a left-hand side elevation of the stand or frame which supports said end of said carrier, including parts and members attached to and supported by said frame, the same being taken on line 3—3, looking in the direction of the associated arrow, in Fig. 5; Fig. 4, a longitudinal, vertical section through portions of the assembling mechanism; Fig. 5, a front side elevation of assembling mechanism which embodies a practical form of our invention as aforesaid; Fig. 6, an enlarged, vertical transverse section through the powder container and valve; Fig. 7, a rear elevation of said assembling mechanism; Fig. 8, a top plan of the slide of said assembling mechanism and of other closely related parts and members, the same being projected from corresponding parts and members in Fig. 7; Fig. 9, a bottom plan of the rear-end portion of said slide and associated parts and members, projected as in Fig. 8 from Fig. 7; Fig. 10, a sectional detail, taken on line 8—8, looking in the direction of the associated arrow in Fig. 8; Fig. 11, a back side elevation of the assembling mechanism, and, Fig. 12, a sectional detail taken on line 12—12, looking in the direction of the associated arrow in Fig. 11.

We have illustrated our assembling mechanism in connection with or as a part of a glaziers-point machine, and will describe so much of said machine as is shown or may be necessary fully to understand said mechanism in both structure and function, although it is to be understood that said mechanism can be applied to or used in connection with a machine or machines other than a glaziers-point machine.

The glaziers-point machine is designed to cut ten metallic strips into diamond-shaped glaziers' points, and to handle ten rows or trains of points after being cut, and the assembling mechanism is provided to separate said trains into ten sticks of 100 points each, at each cycle of operation of the machine.

and mechanism. It is to be understood, however, that the number ten as applied to the assembling mechanism might be increased or decreased without changing any essential 5 feature of said mechanism or departing from the invention. Even a single train of points or other objects might be fed to the assembling mechanism and by the same separated into sticks each of a predetermined length 10 and which is transferred or passed on to be boxed or otherwise disposed of, or mechanism might be built to handle the single train and the single stick; and it naturally follows that mechanism might be constructed to handle 15 more than ten sticks. The ten-unit mechanism is the best for most practical purposes.

Inasmuch as the strips from which the points are cut are fed vertically to the cutters, and it is essential, after the first cut is made, 20 to produce a plurality of glaziers' points at each stroke of said cutters, it is necessary that the cutter-head or cutting mechanism be set obliquely to the vertical plane of the strips when they are fed to the cutters. And since 25 it is preferred that each point be equal in width between either pair of its oppositely disposed edges to the width of the strip from which the point is cut, the cutter-head is set at an angle of 40° to the vertical plane of said 30 strip, that being the degree angle of said parallel edges of said point when the latter is placed vertically on one of said edges.

A table 1 may be used on which to support the machine, including parts and members 35 of the assembling mechanism. A bed block 2 is mounted on and secured to the table 1 adjacent to the right-hand or front end of said table, and a frame 4 is mounted on and secured to said table at the left-hand or rear 40 end thereof. The side of the frame 4 that is toward the front end of the table is the part of said frame which is directly supported on said table, and the other portions of the frame extend rearwardly and upwardly from the opposite end of said table. The frame inclines a little toward the front 45 end of the table. Extending from the frame at the bottom, beyond the rear end of the table, is an arm 5 in front and a brace 6 behind for said arm; and extending from said frame near the upper end, in front, is an arm 7. A slide 8 is securely attached to the outer 50 terminals of the arms 5 and 7.

The slide 8 extends beyond and away from 55 the table 1. As shown in Figs. 7 and 11, the brackets 6 and 7 support and hold the slide so that it is inclined downwardly throughout its length and at the same time inclines transversely of its length at the forward side of 60 the machine.

A portion of the bed block 2 inclines at an angle of 40° downwardly from the rear to the front side of the machine to provide a bed 9 for a cutter-head represented at 14. Bolted 65 to two lugs 9' at the right-hand end of the bed

9 are two bearings 11 in which is journaled a shaft 13, the same being the main drive shaft for the cutter-head 14, and for the movable parts of the assembling mechanism.

Mounted on and secured to the bed block 2 is a bracket 15. Having their bases firmly seated in the bed block 2 are posts 16, and these posts are rigidly connected by a platform 17 on which is mounted a motor 18. The bracket 15 is in front of the posts 16. Secured to the post 16 that is nearer to the front end of the machine is a bracket 19 that extends toward the front side of the machine. Secured to the posts 16 which are adjacent to the back side of the machine, below the platform 17, is a support 20 for a switch 21 by means of which the motor current is turned on and off. Secured to the post 16 at the rear of the one which carries the support 20, but below said support, is a bracket 22 75 that extends toward the rear end of the machine, and has a bearing 23 for the forward terminal of a shaft 24. The bracket 22 extends upwardly at the outer terminal and the bearing 23 is formed at the top of this 80 upwardly extending part, but said bearing has an inclination to the top of the table lengthwise, with the higher end of said bearing towards the front end of the table. Secured to the back side of the frame 4 is a 85 bracket 25 having a bearing 26, inclined like the bearing 23, for the rear terminal of the shaft 24, said first-named bearing therefore being on a lower level than the other. Thus 90 it is seen that the shaft 24 inclines downwardly and rearwardly from the front to the rear end thereof, and is located behind and above the vertical plane of the back side and the horizontal plane of the top of the table 1, respectively. The shaft 24 is provided with 95 a ball-bearing 27 at the inner end of the bearing 26, through the medium of which ball-bearing said shaft is prevented from moving in the direction of its length rearwardly in said bearing, but the means of prevention is of the anti-friction type so that it 100 does not materially interfere with the rotation of the shaft.

The motor 18 has a shaft 28 which extends outwardly on the back side of the machine, 105 and a pulley 29 is mounted on and secured to said shaft. The pulley 29 is connected by means of a belt 30 with a similar pulley 31 below. The pulley 31 is mounted on and secured to a horizontal shaft 32. The shaft 110 32 is journaled in two bearings 33 at the top of a movable carrier 34 held against the front side of the upstanding part of the bracket 15 by means of two bolts 35 which pass through the two vertical slots 36 in said carrier, said 115 bolts being sufficiently loose to enable the carrier to be raised and lowered. The pulley 31 is at the outer end of the shaft 32, and mounted on and secured to said shaft at the inner end is a small friction cone 37. Mount- 120

ed on and secured to the cutter-head shaft 13 is a worm 38, and intermeshing with said worm is a worm-wheel 39 mounted in and secured to a short shaft 40 at the outer end 5 thereof, the inner end of said short shaft being connected by means of a universal-joint 41 with the forward terminal of the shaft 24. The bracket 19 has at the outer end a bearing 42 for the shaft 40. Mounted on 10 and secured to the shaft 13, in front of the worm 38, is a large friction cone 43 which is driven by the friction cone 37 when in engagement with the large cone. Mounted on 15 and secured to the shaft 24 at the rear terminal is a worm 44, and this intermeshes with a worm-wheel 45 mounted on and secured to a transverse shaft 46. The worm 44 is contiguous with the outer end of the bearing 26. The shaft 46 is journaled in 20 bearings provided at the rear ends of a pair of brackets 47 that extend outwardly from the uprights of the frame 4. The shaft 46 extends beyond the frame 4 to position the worm-wheel 45 over the worm 44.

25 The carrier 34 has a vertical bolt 48 tapped into and through the horizontal part of the same, which bolt is provided with a check-nut over said horizontal part. The lower, protruding end of the bolt 48 bears on a cam 50 which has a depending stem 51 that is journaled in the base of the bracket 15. The cam 50 has a tail-piece which extends to the left, and is provided with a depending rod 52. Pivottally connected with the lower 30 end of the rod 52 is a link 53, and pivotally connected with the forward end of said link is a horizontal operating rod 54 provided at its forward end with a handle 55. The rod 54 is supported and adapted to slide in a 35 guide 56 secured below the forward, lower lug 9' to the side of the bed block 2 from which said lug projects.

The form of the cam 50 and the construction and arrangement of the operating members therefore are such that, when the rod 54 is drawn forwardly, said cam, through the medium of the link 53 and the rod 52 is partially rotated in the bearing for the stem 51 in a manner to permit the bolt 48 and the 40 parts supported thereby to descend, and thus move the friction cone 37 from engagement with the friction cone 43 and disconnect the cutter-head shaft 13 with all the parts and members driven and operated by said shaft; 45 and, when said first-named rod is positioned rearwardly, said cam, through the same medium as before, is actuated in the opposite direction and raises said bolt and the aforesaid parts and members far enough to cause 50 said first-named cone to engage said second-named cone, whereby said shaft and members driven and operated thereby are set in motion. The weight of the carrier 34 and the parts and members supported thereby is sufficient to cause the same to descend when the

cam 50 is actuated by the rod 54 in being drawn forward. The slots 36 in the carrier 34 permit of the vertical movement of said carrier as just explained. This movement is comparatively slight, and the belt 30 is sufficiently loose to permit of said movement, but not so loose as to fail to drive the pulley 31 and the shaft 32 when the carrier 34 is in elevated position.

It will now be seen that the motor shaft 28 drives the shaft 32 through the medium of the pulleys 29 and 31 and the belt 30; and that, when the cone 37 is in engagement with the cone 43, the shaft 13 is driven and with it the worm 38, that said worm drives the worm-wheel 39, the shaft 40, the universal-joint 41, and the shaft 24, and that said last-named shaft, through the medium of the worm 44 and the worm-wheel 45, drives the shaft 46. The shaft 46 is a cam shaft from 75 which is operated the movable parts of the assembling mechanism. The universal-joint 41 is necessary because of the presence of the worm 38 and the worm-wheel 39 and the angular relationship existing between the 80 shaft 40 and 13.

A suitable fixed carrier extends between the cutter-head 14 and the frame 4, and the rear-end portion of said carrier, which is the portion connected with and supported by 85 said frame, is indicated by the numeral 57. In the carrier 57 are ten longitudinal channels 58 to receive ten trains of points cut and moved into the same from the cutter-head. The channels open through opposite ends of 90 the carrier 57.

It is customary to apply wax to the points, as they move through the intermediate portion of the carrier 57, for the purpose of causing said points to adhere to each other. 105 The points are cemented together temporarily for convenience in packing them in boxes, and in transferring them from the boxes to the drivers with which the points are applied to window sashes. The channels 110 58 at and adjacent to their left-hand ends open through the bottom of the carrier 57 as represented at 59 in Figs. 3, 7, and 11. Surplus wax pushed along by the trains of points to the rear end of the carrier is received in the slots 59 and from time to time is picked therefrom. The carrier 57 longitudinally inclines upwardly to the frame 4, and said carrier inclines transversely downwardly and forwardly from back to front.

The upward inclination is for the purpose of preventing the trains of points from breaking apart or opening before they arrive at the rear end of said carrier, as they might possibly do were said carrier horizontal, and the inclination in the other direction, that is, transversely, is necessary because of the peculiar setting of the cutting mechanism here required in order to produce diamond-shaped points.

The inner end of the slide 8 is somewhat remote from the adjacent end of the carrier 57, but said slide end is positioned transversely at an angle of 40° as is said carrier end, and arranged to move between said ends and having the same degree of inclination is a movable carrier 60, said movable carrier necessarily being narrower than the space between said ends. At the lower, outer end 10 of the slide 8 is horizontal. The slide 8 has ten longitudinal channels 61 therein, and the carrier 60 has the same number of channels 62 in the upper front side of the same. The channels 62 align with the rear ends of the channels 58 in the fixed carrier 57, when the movable carrier 60 is against the rear end of said fixed carrier, the movable carrier then having the same inclination, in the direction of its channels, as that of the fixed carrier, and said first-named channels align with the 15 inner, upper ends of the channels 61 in the slide 8, when said movable carrier is against the inner, upper end of said slide, the movable carrier then having the same inclination, in the direction of its channels, as that of said 20 slide.

It is to be observed that the slide 8, as illustrated in connection herewith, is somewhat conventionalized, inasmuch as actually said slide with its channels is curved from the 30 forty degrees at the inner end to the horizontal at the outer end.

The frame 4 has a head 63 at the top, which head is constructed to support the rear terminal of the carrier 57, and support the same 35 at the required angle. The extreme rear-end portion of the carrier extends outwardly beyond the head 63, and it is in this portion that the slots 59 are located.

Bolted to the uprights of the frame 4 are 40 two angular brackets 64 having at their rear ends up-turned arms in which is a rock shaft 65. The supporting arm 7, for the slide 8, is adjustably bolted to the front bracket 64. Mounted on and secured to the rock-shaft 65 45 is a bell-crank-lever 66 having at the top a cross arm 67 on and to which the movable carrier 60 is mounted and rigidly secured. A peripheral cam 68, consisting largely of a dwell, is mounted on and secured to the cam 50 shaft 46, between the arms 47. Journaled in the lower portions of the brackets 64 is a rock-shaft 69. Mounted on and secured to the rock-shaft 69 is an arm 70 provided with 55 a cam plate 71 arranged to bear on the periphery of the cam 68, and being held in contact with said periphery by means of a spring 72 attached at the upper end to said arm and at the lower end to the supporting arm 5.

60 A link 73 has its upper end pivoted at 74 to the short, rearwardly extending arm of the bell-crank-lever 66, and its lower end pivoted at 75 to the outer end of the arm 70.

At each revolution of the cam 68 the cam 65 plate 71 drops into the depression in said

cam, and the arm 70 swings downwardly on the rock-shaft 69 and carries with it the link 73, and by said link the bell-crank-lever 66 is rocked on the rock-shaft 65 in the direction to move the carrier 60 from the rear end of 70 the fixed carrier 57 to the inner end of the slide 8, and said plate is forced out of said depression as the high part of said cam passes beneath said plate, said arm is swung upwardly against the resiliency of the spring 72, and, through the medium of said link and said bell-crank-lever, said movable carrier is moved to the right again against said end of 75 said fixed carrier, there to remain until said cam depression arrives a second time beneath said plate. What may be termed the normal position of the movable carrier 60 against the fixed carrier 57 is as indicated in Fig. 11. The cam 68 causes the carrier 60 to contact somewhat forcibly with the slide 8 and thereby to 80 produce a jar.

The trains of points move rearwardly in the channels 58 in the carrier 57, pass under a separator blade 76 and into the channels 62 in the movable carrier 60, until there are 90 one hundred points in each channel 62, and then they are cut into lengths or sticks each consisting of said one hundred points. The carrier 60 is then actuated over against the slide 8, and strikes said slide with force 95 enough to produce the slight jar that with gravity causes the sticks to slip from the movable carrier channels into the slide channels 61.

The movable carrier 60 is provided with 100 two rods 77 that pass transversely across the channels 62 in said carrier, and prevent the sticks from being thrown out of the open sides of said channels.

The separator blade 76, which is necessarily 105 inclined at 40°, is bolted to the under side of a support or holder 78 which extends upwardly from said plate, and has on the inner side thereof at the ends sleeves 79 and 80 mounted to slide up and down on guide rods 110 81 and 82, respectively, said rods rising from the frame head 63 adjacent to the side thereof that is adjacent to and parallel with the rear end of the carrier 57. Encircling the rod 81, between the head 63 and the base of the sleeve 115 79, is a spring 83. The spring 83 normally retains the holder 78 with the blade 76 in its elevated position, and tends constantly to restore it to said position when depressed. The upper terminal of the rod 81 is screw threaded to receive a nut 84 above the sleeve 79, which nut serves as an adjustable stop to 120 limit the upward movement of the holder 78.

The holder 78 is depressed, against the resiliency of the spring 83, and with the sleeves 125 79 and 80 sliding on the rods 81 and 82, by means of an approximately vertical bar 85 provided on the inside with a dog 86, and a trip-arm 87. The bar 85 is arranged to slide up and down in slots in a boss 88 on the front 130

of the arm 5 and in the head 63 above, and behind straps 89—89 fastened to said boss and head over said slots. The bar 85 is connected with the base of the sleeve 79 by means of a bolt 90 passing through a longitudinal slot 91 into said bar. A washer 92 is mounted on the bolt 90 between the head of said bolt and the bar 85. The slot 91 permits the bar 85 to be adjusted relative to the holder 78, and the stroke of the blade 76 correspondingly varied. The nearer the bottom of the slot 91 is to the bolt 90 the lower the blade 76 is carried on its downward stroke, and vice versa. The dog 86 is located on the bar 85 a little above the boss 88. The trip-arm 87 is mounted on and secured to the cam-shaft 46 above the boss 88, and the dog 86 is in the path of the outer terminal of said arm.

At each revolution of the cam shaft 46 and of the trip-arm 87, said trip-arm encounters the dog 86 and causes the bar 85 to move downwardly momentarily, and said bar is carried with it, against the resiliency of the spring 83, the members mounted to slide on the rods 81 and 82, with the result that the blade 76 is carried downwardly at the proper time to sever the 100 points on the movable carrier 60 from the trains in the fixed carrier 57. At this time the movable carrier 60 is located against the rear end of the carrier 57, and the instant the one thousand points have passed into the movable-carrier channels 62 (100 from each channel 58 into each channel 62) the blade 76 descends. This action of the blade 76 produces ten sticks of points. The descent and return of the blade 76 is almost instantaneous, otherwise the points, which are continuously being fed out of the channels 58 in the carrier 57, would jam against the blade. As soon as the blade 76 has severed the ten sticks of points, which sticks upon being severed drop into the channels 62 in the carrier 60, said carrier is actuated by the cam 68 and the spring 72 over against the slide 8 and deposits said sticks by shock and gravity in the slide channels 61. The ten sticks of points from the carrier 57 are pushed or fed out into space a short distance, but the carrier 60 is returned quickly by the cam 68 into supporting and receiving position beneath the protruding portions of said sticks.

Although the blade 76 oscillates in an approximately vertical plane it is inclined lengthwise, as previously noted.

It is by means of the blade 76 that the mechanical count of the machine equipped with this mechanism is obtained, since said blade is timed one hundred to one with the mechanism for cutting and feeding the points into the channels 58 in the carrier 57. At each downward movement of the blade, therefore, 100 points from each of the ten trains are cut off.

To facilitate the movement of sticks of

points after they have been severed from their trains, a container 93 for powder is provided, together with means for discharging the powder onto the sticks. The container 93 is fastened to an arm 94 which in turn is secured to the part of the head 63 from which the rod 82 rises. The sides of the container 93 converge from above downwardly, and in the bottom of said container are perforations 95. A roller valve or agitator 96 is located on the bottom of the powder container, and said agitator has a rigidly attached finger 97 which extends downwardly therefrom through a slot 98, Fig. 7, in said bottom. The agitator 96 is provided with sets of radial perforations 99 arranged therein so that those in one set are in a plane which intersects the plane in which those in the other set are located, and those in one set are over the perforations 95 in the container 93, when the agitator is disposed in one extreme position, and those in the other set of said first-named perforations are over the second-named perforations, when said agitator is disposed in the other extreme position—see Fig. 6. Fastened to the upper or rear side of the slide 8 adjacent to the inner end thereof is a spring-pressed latch 101 which carries a rod 102, and the agitator finger 97 is in the path of said rod. The container 93 is inclined like the blade 76 and certain of the other parts.

In the backward and forward movement of the carrier 60, the rod 102 encounters the finger 97 and said finger causes the agitator to be oscillated, whereby the powder in the container 93 is agitated and a certain portion of the same is caused each time to escape, by way of one or the other sets of openings 99 and through the openings 95, onto the points below.

By gravity the ten sticks that have been deposited in the channels 61 in the slide 8 move down said slide until the leading ends of said sticks arrive at a downwardly extending lip 103 at the lower or outer side edge of a movable stop 104, said lip normally being against the rear ends of said channels. An arm 105 extends from the center of the top of the stop 104 toward the back side of the slide 8, and is rigidly secured at its outer end to the rear end of a plunger 106 mounted to slide and rock in two bearings 107 at the outer ends of two arms 108 bolted to the under side of said slide. The stop 104, when in normal position, extends across the top of the slide 8 adjacent to the lower, rear, or outer end thereof, with the lip 103 against the extreme outer end of said slide, and the ends of said cross rods 109, with which said stop is provided, then rest on a pair of tracks 110 having their inner ends secured to the top of the slide 8 adjacent to said end. The tracks 110 extend downwardly and rearwardly beyond the slide. The rods 109 project beyond both ends of the stop 104 to bear and

ride on the tracks 110. A sleeve 111 is mounted on the plunger 106 between the bearings 107, and is keyed to said plunger in order to enable the latter to slide in said sleeve, and 5 also, when partially rotated to rock said sleeve with it—see Fig. 11. It follows, therefore, that, when the plunger 106 is moved longitudinally, it carries with it the stop 104, the rods 109 then riding on the tracks 110; and, 10 when said plunger is rocked in one direction, it swings said stop upwardly, through the medium of the arm 105 and the sleeve 111, and, when said rod is rocked in the opposite direction, said stop is returned to its former 15 position with said rods on said tracks.

A curved lever 112 has its rear end pivotally connected at 113 with the upstanding parts of the frame 4, and is provided on the back side intermediate of the ends with a 20 cam roll 114. A link 115 is pivotally connected at the inner end, as at 116, with the upper terminal of the lever 112, and has its opposite end pivotally connected at 117 with the inner or rear terminal of the plunger 25 106. Secured to the back side of the cam 68 are two cam plates 118 and 119 which form between them a cam groove 120 for the roll 114.

As the lever 112 is oscillated by the roll 30 114 in the cam groove 120, at each revolution of the cam 68, the link 115 is caused to impart an oscillatory movement to the plunger 106, and through said plunger and the arm 105 to the stop 104. The dwell in the 35 cam-groove 120 is such that the stop 104 is retained in retracted position during about one-half of the revolution of said cam.

A bent rod 121 extends radially from the under side of the sleeve 111, and then upwardly and forwardly to have its free terminal received in a notch 122 in the free terminal of a lever 123. The lever 123 at its rear end is mounted on the same pivot rod 40 113 with the lever 112, and said first-named lever is provided with a roll 124 which is in the path of a segmental cam plate 125 secured to the front side of the cam 68.

At each revolution of the cam 68, and 45 while the cam plates 118 and 119 are causing the stop 104 to be reciprocated and said stop is in its most rearward position, the cam plate 125 encounters the roll 124 and rocks the arm 123 upwardly on the pivot 113, and said arm carries with it the connected terminals of the arm 121 and thus rocks the sleeve 111 and the plunger 106, with the result that the arm 105 is swung upwardly with 50 said plunger and raises said stop into the position shown in Fig. 11. As soon as the cam plate 125 passes beyond the roll 124, the lever 123 rocks downwardly, and, through the medium of the arm 121 imparts a partial revolution in the opposite direction to the sleeve 111 and the plunger 106, whereby the 55 stop 104 is swung down until the rods 109

come to rest on the tracks 110. The arm 105 has a pivotal connection at 126 with the stop 104, and the tracks 110 at their inner terminals are slightly elevated, as shown at 60 127—127, whereby said stop is raised at the upper or inner side when moved into its extreme forward position, so that the stop can interpose no obstruction to the sticks of points as they slide under the same—see Fig. 65 4. In other words, the stop 104 is tilted to receive between it and the slide 8 the ten sticks of points and permit them to move down against the lip 103.

A support in the form of a shallow trough 70 129 is rigidly secured at its inner end to the outer end of the slide 8, and this trough receives the sticks as they slide down with the stop 104, and after said stop releases said sticks they continue to slide until they encounter a gate 130. The end of the trough 75 129 which is in contact with the slide 8 corresponds in width with the combined width of the channels 61 at their rear ends, but said sides converge toward the opposite ends of said trough, so as to cause the sticks, as they slide down in said trough, to come together and close the spaces made by the channel 80 partitions of the slide.

The gate 130 is a thin plate that extends 85 across the trough 129, and the upper end of said gate is clamped to the rear end of an arm 131 which extends rearwardly from the horizontal part of a U-shaped rocker 132 mounted on and extending above the slide 8. One downwardly extending arm of the rocker 132 is pivotally connected at 133 with the back side of the slide 8 near the lower end thereof, and the other downwardly extending arm of said rocker is rigidly attached to the upper part of a curved arm 134 which is pivotally attached at 135 to said slide diametrically opposite to the pivot 133. The arm 134 extends downwardly and forwardly, and has at the forward end a pin 136 which is received in a slot 137 in the free end of a lever 138. The lever 138 is pivotally connected at 139 with the frame 4, below the pivot 113, and said lever is provided with a roll 140 which is in the path of the portion of the outer edge of the cam 68 that assists in forming the high part of the cam 90 groove 120, such part being indicated at 141. Normally the gate 130 rests on the trough 129, and at such time the roll 140 is out of contact with the cam plate 119, but, when the cam edge 141 of said plate encounters said roll, the lever 138 is rocked downwardly on the pivot 139, imparts a downward movement to the arm 134, and thus rocks 95 said arm and the rocker 132 on the pivots 133 and 135 forwardly, and causes the arm 131 and said gate to be raised into the position shown in Fig. 11. As soon as the cam edge 141 passes clear of the roll 140, the lever 138 is rocked upwardly, and, acting 100

through the arm 134 and the rocker 132, swings the arm 131 and the gate 130 downwardly until said gate rests on the trough 129.

- 5 The lever 123 is yieldingly held in its downward position by means of a spring 128 having the upper end attached to said lever and the lower end attached to the brace 6, and the lever 138 is yieldingly retained in its elevated position by means of a spring 142 having the upper end attached to the frame 4 and the lower end attached to said last-named lever.
- 10

In practice, when ten sticks of points in the channels 61 arrive against the lip 103 of the stop 104, the latter with said stick moves downwardly, the sticks sliding from said channels into the trough 129, said stop is elevated and releases said sticks which continue to slide down in said trough until 20 they contact with the gate 130, said gate is raised, and the sticks, still in the trough, move on by gravity.

During each cycle of the mechanism, the stop 104 is swung down with its supporting rods 109 on the tracks 110 and actuated until the lip 103 is against the rear end of the slide 8, and the gate 130 is lowered into the trough 129.

The operation of the mechanism as a whole 30 is described as follows: The switch 21 is thrown to set the motor 18 in motion, and the rod 54 is forced rearwardly to elevate the friction cone 37 into engagement with the friction cone 43. The driving and driven 35 parts of the mechanism are now in motion. As the points are cut they force those previously cut and already in the channels 58 in the fixed carrier 57 along in said channels in trains. These trains first pass through a hot 40 wax, cementing compound and eventually pass at their rear ends beneath the separator blade 76 and into the channels 62 in the movable carrier 60. As soon as the movable carrier 60 is loaded the blade 76 is caused to 45 descend and cut or separate the parts of the trains or the pluralities of points in said carrier into ten sticks of 100 points each, it being understood that said blade operates while the movable carrier is in position against the 50 rear end of the fixed carrier, and as soon as one thousand points have passed into the movable carrier channels. Then the carrier 60, which is operated by the cam 68 and the intervening mechanism, is moved against the 55 upper, inner or forward end of the slide 8, striking the same with an impact sufficiently forceful to insure the transfer of the ten sticks from said carrier to said slide. By gravity these sticks slip down in the channels 60 61 in the slide 8 into contact with the lip 103 of the stop 104. By means of the cam plates 118 and 119 and the mechanism operated thereby, the stop 104 is carried down and with it the sticks retarded by the lip 103, until said 65 stop is elevated by means of the cam plate

125 and the mechanism operated thereby, when said sticks slide down against the gate 130, the sticks during this time being in the trough 129, having passed into the same as soon as they left the slide 8. From the trough 129 the sticks are delivered or passed to the boxing mechanism of the glaziers-point machine, but may be delivered for disposal otherwise than by being packed in boxes. Before the ten sticks in the next leading set arrive 70 at the lower ends of the channels 61, the stop 104 is returned to position to receive said sticks as before. The second cycle of the mechanism follows the first with similar results, and so on indefinitely.

80 We claim:

1. In mechanism of the class described, a carrier for a plurality of objects, a slide for said objects, said carrier and slide being arranged with a gap between their adjacent ends, and a spring actuated member in said gap movable toward said end of said carrier and toward said end of said slide, to receive said objects, transfer them to said slide, and deliver them to said slide by a jarring contact with said end thereof.

85 2. In mechanism of the class described, a fixed carrier, a movable carrier for objects, a cutter-head shaft, separating means, an inclined slide, adjacent ends of said fixed carrier and slide being spaced apart, and said movable carrier being arranged to oscillate in such space, and operating means for said shaft, said movable carrier, and said separating means, said operating means being timed to cause said separating means, to cut off a predetermined number of objects after they have arrived on said movable carrier, to swing said carrier toward said end of said slide and back toward said end of said fixed carrier, at the end of the number of cycles of said shaft which corresponds with the number of objects cut off by said separating means.

90 3. In mechanism of the class described, a fixed carrier for objects, a movable carrier for said objects, a cutter-head shaft, separating means, an inclined slide between which and said fixed carrier said movable carrier oscillates, a movable stop for the objects delivered by said movable carrier to said slide, and a support for said objects after they leave said slide, and operating mechanism for said shaft, said movable carrier, said separating means, and said movable stop, said operating mechanisms being timed to cause said separating means to cut off a predetermined number of objects when they arrive on said movable carrier, to rock said movable carrier into operative position relative to said slide and back into operative position relative to said fixed carrier, and to operate said stop to permit the objects on said slide to move onto said support, release them, and

100 105 110 115 120 125 130

be returned to initial position, at the end of

the number of cycles of said shaft which corresponds with the number of objects cut off by said separating means.

4. In mechanism of the class described, an inclined slide, an inclined support at the lower end of said slide, a reciprocating and oscillating member to control the movement of objects from said slide onto said support, an oscillatory gate adapted to stop said objects on said support after being released by said member, and operating mechanism, for said member and gate, timed to actuate the member to release the objects while the gate is in operative position, and subsequently to move said member to initial position and oscillate said gate.

5. In mechanism of the class described, a cutter-head shaft, a cam shaft, means to drive said cam shaft from said cutter-head shaft, a separator blade, operating means for said blade, a fixed carrier, an inclined slide, the adjacent ends of said carrier and slide being spaced apart, a movable carrier arranged to oscillate in the space between said fixed carrier and said slide, operating means for said movable carrier, and members on said cam shaft to actuate the operating means for said blade and the operating means for said movable carrier.

- 30 6. In mechanism of the class described, a cutter-head shaft, a cam shaft, means to drive said cam shaft from said cutter-head shaft, a separator blade, operating means for said blade, a fixed carrier, an inclined slide, an inclined support at the lower end of said slide, a movable carrier arranged to oscillate between said fixed carrier and said slide, operating means for said movable carrier, a stop to control the movement of points from 35 said slide onto said support, operating means for said stop, and members on said cam shaft to actuate the operating means for said blade, the operating means for said movable carrier, and the operating means for said stop.

- 45 7. In mechanism of the class described, a cutter-head shaft, a cam shaft, means to drive said cam shaft from said cutter-head shaft, a separator blade, operating means for said blade, a fixed carrier, an inclined slide, an inclined support at the lower end of said slide, a movable carrier arranged to oscillate between said fixed carrier and said slide, operating means for said movable carrier, a reciprocating and oscillating stop to control 50 the movement of points from said slide onto said support, means to reciprocate said stop, means to oscillate said stop, and members on said cam shaft to actuate the operating means respectively for said blade, said movable carrier, said stop in its reciprocating movement and said stop in its oscillatory movement.

- 60 8. In mechanism of the class described, a cutter-head shaft, a cam shaft, means to drive said cam shaft from said cutter-head shaft, a separator blade, operating means for said

blade, a fixed carrier, an inclined slide, an inclined support at the lower end of said slide, a movable carrier arranged to oscillate between said fixed carrier and said slide, operating means for said movable carrier, a 70 movable stop to control the movement of points from said slide onto said support, operating means for said stop, a gate to control the movement of said points on said support, operating means for said gate, and members on said cam shaft to actuate the operating means respectively for said blade, said movable carrier, said stop, and said gate.

9. In mechanism of the class described, a cutter-head shaft, a cam shaft, means to drive said cam shaft from said cutter-head shaft, a separator blade, operating means for said blade, a fixed carrier, an inclined slide, an inclined support at the lower end of said slide, a movable carrier arranged to oscillate between said fixed carrier and said slide, operating means for said movable carrier, a movable stop to control the movement of points from said slide onto said support, means to reciprocate said stop, means to oscillate said stop, a gate to control the movement of said points on said support, means to oscillate said gate, operating means for said stop, and members on said cam shaft to actuate the operating means for said blade, the operating means for said movable carrier, said stop-reciprocating means, and said stop-oscillating means.

10. The combination, in mechanism of the class described, with a support, a carrier movable on said support, a cam arranged to move said carrier, means for actuating said cam, a driven shaft journaled in said carrier, and a driving member on said shaft, of a cutter-head shaft, and a driven member on said cutter-head shaft, said driving member being adapted to engage said driven member when said carrier is located in one position by said cam, and to disengage said driven member when said carrier is located in another position by said cam.

11. The combination, in mechanism of the class described, with a carrier for trains of objects, of movable means adapted to receive the leading-end portions of said trains, a blade slidably arranged above said trains, and means to actuate said blade and cut off said portions, when a predetermined number of objects has passed from said carrier onto said movable member.

12. The combination, in mechanism of the class described, with a carrier for trains of objects, of a frame, a spring-pressed holder mounted on said frame, a blade carried by said holder above said trains of objects, at one end of said carrier, a bar provided with a dog, connected with said holder, and supported to reciprocate on said frame, a shaft journaled in said frame, and an arm secured 125

to said shaft, said dog being in the path of said arm.

13. The combination, in mechanism of the class described, with a transversely-inclined carrier for trains of objects, of a frame, a spring-pressed holder mounted on said frame, a blade carried by said holder above said trains of objects, at one end of said carrier, a bar provided with a dog, connected with said holder, and supported to reciprocate on said frame, a shaft journaled in said frame, and an arm secured to said shaft, said dog being in the path of said arm.

14. The combination, in mechanism of the class described, with a carrier for trains of objects, and a blade at one end of said carrier adapted to cut sticks of predetermined lengths from said trains, of an inclined slide adapted to receive said sticks, a frame, a movable carrier supported from said frame, a shaft journaled in said frame, a cam on said shaft, and means to operate said movable carrier from said cam, whereby said movable carrier is oscillated to receive sticks from said fixed carrier and deliver them to said slide.

15. The combination, in mechanism of the class described, with a fixed carrier for trains of objects, and a blade at one end of said carrier adapted to cut sticks of predetermined lengths from said trains, of an inclined slide adapted to receive said sticks, a frame, a movable carrier between adjacent ends of said fixed carrier and said slide, and supported from said frame, a shaft journaled in said frame, a cam on said shaft, and means to operate said movable carrier from said cam, said cam being shaped to cause said movable carrier normally to be held against said end of said fixed carrier, and to oscillate said movable carrier momentarily, whereby the same contacts with the adjacent end of said slide and returns to position against said end of the fixed carrier.

16. The combination, in mechanism of the class described, with a fixed carrier for trains of objects, and a blade at one end of said carrier adapted to cut sticks of predetermined lengths from said trains, of an inclined slide adapted to receive said sticks, a frame, a shaft supported from said frame, a bell-crank-lever mounted on said shaft, a movable carrier mounted on said bell-crank-lever between said fixed carrier and said slide, a second shaft supported from said frame, a cam on said second shaft, a cam arm supported from said frame and having a part in engagement with said cam, and a link connecting said bell-crank-lever and said arm, the construction and arrangement of parts being such that said movable carrier is oscillated to receive said sticks from said fixed carrier and deliver them to said slide.

17. The combination, in mechanism of the class described, with a fixed carrier for trains of objects, a blade adapted to cut sticks from

said trains at one end of said carrier, and a perforated container for powder supported above and adjacent to said end of said carrier, said container being provided with agitator means consisting in part of a finger, of a slide, and a carrier, for said sticks, movable between adjacent ends of said fixed carrier and said slide and beneath said receptacle, said movable carrier being provided with a projecting part to engage said finger and operate said agitating means as said movable carrier is actuated.

18. In mechanism of the class described, a fixed carrier and slide having adjacent inner ends in spaced relation, the said slide being disposed in a plane opposed to that of the carrier and having a plurality of grooves extending longitudinally thereof, a carrier between said inner ends of less length than the distance therebetween adapted and mounted for swinging movements so as to align with either said carrier or slide, an ungrooved support at the outer end of said slide, a stop movable longitudinally of said support to facilitate the movement of objects therealong from the grooves of the slide and guides extending along said support from said slide arranged in converging relation to urge objects into closely adjacent relation.

19. In mechanism of the class described comprising in combination, a fixed carrier and a slide having adjacent inner ends in spaced relation, a container having an outlet disposed above said end of said carrier, a movable agitator in said container having an actuating member, a carrier movable between the adjacent ends of said carrier and slide having a part for engaging said actuating member.

20. In mechanism of the class described comprising in combination, a fixed carrier inclined transversely of its length, a slide inclined longitudinally and transversely, the adjacent inner ends of said carrier and slide being spaced from one another, a container having an outlet side disposed above the space between said ends, an agitator movable in said container having an actuating member outside said container, a carrier movable between said carrier and slide arranged so that its opposite sides may alternately engage the ends thereof and means associated therewith for engaging said actuating member.

CHARLES J. FANCHER.
ROBERT A. JOHNSON. 120
